CLAIM

The ornamental design for a vegetable slicer as shown and described.

DESCRIPTION

2. Vegetable slicer
2.1: Perspective
2.2: Perspective
2.3: Front
2.4: Back
2.5: Left
2.6: Right
2.7: Top
2.8: Bottom
2.9: Exploded
2.10: Top perspective view in alternate configuration
2.11: Top perspective view in alternate configuration
2.12: Top perspective view in alternate configuration
The dash-dash broken lines in the drawings depict the portions of the vegetable slicer that form no part of the claimed design.

1 Claim, 9 Drawing Sheets
